UNITED STATES PATENT OFFICE.

JOHN C. CROMWELL AND CARL W. A. KOELKEBECK, OF CLEVELAND, OHIO,
ASSIGNORS OF THREE-FOURTHS TO THE GARRETT-CROMWELL ENGINEERING COMPANY, OF CLEVELAND, OHIO, A CORPORATION OF OHIO.

BLAST-FURNACE-CHARGING APPARATUS.

SPECIFICATION forming part of Letters Patent No. 727,753, dated May 12, 1908.

Application filed July 29, 1902. Serial No. 117,428. (No model.)

To all whom it may concern:

Be it known that we, JOHN C. CROMWELL and CARL W. A. KOELKEBECK, of Cleveland, Cuyahoga county, Ohio, have invented a new and useful Blast-Furnace-Charging Apparatus, of which the following is a full, clear, and exact description, reference being had to the accompanying drawings, forming part of this specification, in which—

10 Figure 1 is a sectional side elevation showing the top of a blast-furnace provided with our improved charging apparatus, and Figs. 2, 3, 4, and 5 are similar views showing a modified form.

15 Our invention relates to the charging of blast-furnaces wherein a double hopper and bell system is used and is designed to provide improved means for distributing the stock within the lower hopper.

20 To that end the invention consists in providing between the two hoppers an annular downwardly and inwardly inclined deflector upon which the stock is discharged by the upper bell.

25 It also consists in certain constructions and arrangements hereinafter more clearly described, and set forth in the claims.

In the drawings, referring to the form of Fig. 1, 2 represents the top plate of a blast-furnace, 3 the main hopper, and 4 the closing-bell therefor. In this form we provide a surrounding casing 5, which extends upwardly from the lower hopper and preferably converges upwardly and inwardly and carries 35 the annular deflector 6. We have shown this funnel or deflector as having an upper flanged member 7 secured between flange members 8 and 9 of the casing. The upper or supplemental hopper 10 is shown as supported at 40 the upper end of the casing and having a closing-bell 11, whose stem 12 is hollow to allow the stem 13 of the lower bell to extend upwardly through it. The arrangement of the bells, with their actuating mechanism, 45 may, however, be widely varied within the scope of our invention. The funnel or deflector 6 is so arranged that when the upper bell is lowered the stock slides therefrom and strikes upon the inwardly-inclined sides of

the deflector. It then slides down the deflector and is inwardly directed to and upon the lower bell. A good central distribution of the stock is thus obtained within the lower hopper before charging it into the furnace.

In Fig. 2 we show a form similar to that of Fig. 1, except that the casing 5' extends inwardly to the lower end of the deflector 6', the deflector thus constituting a part of the casing between the upper hopper 10' and the lower hopper 3'.

In Fig. 3 we show a form similar to that of Fig. 2, except that the deflector 6'' is extended into an annular projecting portion 14 at its lower end, giving an inner overhanging portion extending beyond the support.

In Fig. 4 we show a form similar to that of Fig. 2, except that two deflectors 6''' are employed, the stock falling from the upper bell upon one deflector and thence sliding inwardly and downwardly to and upon the next deflector, where it is again distributed, and thence slides to and upon the lower bell.

In Fig. 5 we show a form similar to that of Fig. 1, except that the lower portion of the deflector 6 is formed of segmental concave plates 15, which are pivoted at their upper ends to the deflector and are held in adjusted position by links 16, connecting them with screw-bolts 17, extending through hand-nuts 18, mounted in the casing. By turning the hand-nuts the pivotal link connections will move the sections in or out and adjust the degree of inclination of the lower part of the deflector and then hold these plates in adjusted position. One point of advantage of this form is that in case the furnace is working irregularly and it is hotter upon one side than the other the operator by adjusting the plates 15 so that they are more sharply inclined upon one side than upon the other can change the distribution and feeding of the stock and remedy this uneven working. This facility for changing the distribution of the stock during the working of the furnace we believe to be new and desire to cover the same broadly.

The advantages of our invention result from the use of the inwardly and downwardly

converging deflector between the two bells, since an even and uniform distribution of stock is thus obtained, and, further, from the means for varying the inclination of parts of the deflector to vary the distribution as desired.

Many variations may be made in the form and arrangement of the hoppers and charging-bells, as well as that of the deflector and the means for supporting it, without departing from our invention.

We claim—

1. In blast-furnace-charging apparatus, an upper bell and hopper, a lower main bell and hopper, and a downwardly and inwardly inclined deflector arranged to receive the stock from the upper hopper and deflect it inwardly upon the lower bell; substantially as described.

2. In blast-furnace-charging apparatus, a lower main hopper, a closing-bell therefor, an upper supplemental hopper, a closing-bell therefor, a casing between the hoppers and a downwardly and inwardly converging funnel arranged to receive the stock from the upper bell and direct it toward the apex of the lower bell; substantially as described.

3. In blast-furnace-charging apparatus, a pair of hoppers in vertical alinement, closing-bells therefor, a casing extending between the hoppers, and an inwardly and downwardly converging deflector supported upon the casing between the hoppers; substantially as described.

35 4. In blast-furnace-charging apparatus, an

upper bell and hopper, a lower main bell and hopper, a downwardly and inwardly inclined deflector arranged to receive the stock from the upper hopper, and connections for adjusting the inclination of at least a part of said deflector; substantially as described.

5. In blast-furnace-charging apparatus, a hopper, a closing-bell therefor, a deflector below the bell and arranged to receive the material therefrom, and connections for changing the inclination of at least a part of said deflectors; substantially as described.

6. In blast-furnace-charging apparatus, a hopper, a closing-bell therefor, an annular deflector below the bell and arranged to receive the stock therefrom, said deflector having a pivoted extension and a connection leading to the extension and arranged to adjust it and hold it in adjusted position; substantially as described.

55 7. In blast-furnace-charging apparatus, an upper bell and hopper, a lower bell and hopper, and a deflector between the hoppers having an annular series of pivoted extensions, said extensions having connections arranged to adjust their inclinations and clamp and hold them in adjusted position; substantially as described.

In testimony whereof we have hereunto set our hands.

JOHN C. CROMWELL.

CARL W. A. KOELKEBECK.
